DUPLEX RAIL ASSEMBLING ELEVATOR

Horace C. Wauson and Walter E. Bennett, Jr.,
Houston, Tex., assignors of one-half to Gulf
Publishing Company, Houston, Tex., a corpora-
tion of Texas

Application August 25, 1947, Serial No. 770,404

6 Claims. (Cl. 199—29)

1

This invention relates to new and useful improvements in duplex rail assembling elevators, and in particular to novel and useful arrangements and structures for the upper rail thereof.

The invention is in some respects an improvement over our previous invention as disclosed and set forth in our Patent No. 2,401,125, issued May 28, 1946, although it may be applied with beneficial and desirable results to many other types of duplex rail assembling elevators.

This invention includes among its objects the objects set forth in the above identified patent. The invention also includes additional objects, an important one being the elimination of lateral movement of the upper rail beyond the limit or outline of the assembling elevator, whereby modification or alteration of a typesetting machine upon which the elevator is positioned is eliminated.

A particular object of the invention is to provide an improved upper rail for a duplex rail assembling elevator wherein provision is made for allowing a portion of the rail to be shifted longitudinally and permit matrices to drop directly onto the lower or bottom rail, such shifting of the upper rail being accomplished without the movement of any portion of said rail beyond the outline or confines of the elevator, whereby the protrusion of any portion of the rail or the elevator in any operating position is eliminated and the necessity for altering or cutting away portions of the typesetting machine upon which the elevator is positioned, is rendered unnecessary.

A further object of the invention is to provide an improved upper rail for a duplex rail assembling elevator wherein the rail is provided with a movable portion carrying a projection for engaging matrices carried upon the elevator, that portion of the rail carrying the projection being laterally shiftable for subsequent direct feeding of matrices onto the lower rail.

Yet another object of the invention is to provide an improved upper rail for a duplex rail assembling elevator having a portion of said upper rail shiftable longitudinally with respect to the balance of the rail, said portion being unimpeded in its movement whereby it may be engaged by a matrix fed into the elevator and shifted longitudinally, and will remain in the position to which it is shifted.

A still further object of the invention is to provide an improved upper rail for a duplex assembling elevator, said rail being laterally shiftable as a unit to expose the lower rail and having a relatively narrow bridging section individually

2

shiftable laterally, said rail including a longitudinally movable section adapted to telescope the non-longitudinally movable portion of the rail to increase the gap provided by lateral movement of the bridging section while continuing to support matrices previously composed upon the upper rail.

Another object of the invention is to provide an improved upper rail of the character set forth 10 wherein the bridging section coacts with the longitudinally shiftable section of the rail to return in a positive fashion the latter section to an unshifted position upon return of the bridging section to a matrix-supporting position.

15 A construction designed to carry out the invention will be hereinafter described together with other features of the invention.

The invention will be more readily understood from a reading of the following specification and 20 by reference to the accompanying drawings, wherein examples of the invention are shown, and wherein:

Fig. 1 is a front elevation of a duplex rail assembling elevator having an upper rail constructed in accordance with this invention.

25 Fig. 2 is an enlarged plan view of the portion of the assembler shown in Fig. 1.

Fig. 3 is a longitudinal, vertical, sectional view, taken on the line 3—3 of Fig. 2.

30 Fig. 4 is an enlarged, transverse, vertical, sectional view, taken on the line 4—4 of Fig. 1, showing a matrix supported upon the upper rail unit.

Fig. 5 is an enlarged, longitudinal, vertical, sectional view, taken on the line 5—5 of Fig. 2, showing the mounting of the upper rail unit within the elevator.

Fig. 6 is an isometric view of the upper rail unit showing the relationship of its sections.

Fig. 7 is an enlarged, fragmentary, isometric 40 view, similar in some respects to Fig. 6, showing the bridging section retracted.

Fig. 8 is a view similar to Fig. 7, showing the bridging section retracted, and the laterally movable section moved away from said bridging section.

Fig. 9 is a vertical, cross-sectional view, taken on the line 9—9 of Fig. 8, and

Fig. 10 is a fragmentary, enlarged, isometric view of a modified form of the bridging section.

50 In the drawings, the numeral 10 designates the frame of the forward portion of duplex rail assembling elevator or assembler which includes a horizontal body or head 11 having an offset depending shank 12. In order to reduce the weight 55 of the shank, the central portion thereof is cut

out in the usual manner. An opening 13 is formed in the lower portion of the shank 12 for receiving a suitable bolt (not shown) so that the frame may be secured to a typesetting machine (not shown). A lower rail 14, of conventional construction, is preferably made integral with the rear face of the head 11 adjacent its upper surface as shown in Fig. 4, said upper surface being substantially flat for receiving an upper rail unit A. A retaining bar 15 overlies the upper rail unit A and is secured to the head 11 by suitable screws 16, whereby said unit is confined between the bar and the upper surface of said head. For spacing the bar relative to the head, small bearing blocks 17 may be interposed therebetween, or made integral with one or the other, and is positioned one at each end of the unit A as shown in Figs. 1, 5 and 6.

The usual gate 18 extends longitudinally above the frame 10 so as to overlie the head 11 and is pivotally secured thereto by upstanding arms or end members 19. A matrix delivery throat 20 is disposed adjacent the right hand end of the frame and a star wheel 21 is positioned therebelow in the conventional manner. The star wheel is adapted to be constantly rotated for controlling the feeding of matrices M from the throat 20 to the rails of the assembler and has its shaft 22 extending parallel and transversely at a right angle to the longitudinal axis of said assembler so that the plane of rotation thereof is also parallel to the longitudinal axis of the assembler.

The upper rail unit A is slidable laterally or transversely upon the flat upper surface of the head 11 and has its forward edge portion projecting beyond the forward face thereof, as is clearly shown in Fig. 4. This lateral or transverse sliding movement of the unit A will project and retract the rear edge portion of said assembly relative to the rear face of the head 11. For laterally moving or retracting the unit, a shaft or rod 23, having a hand lever 24 secured thereto, is disposed forwardly of the head below said unit and is rotatably journaled within suitable bearing collars 25 which are preferably formed integral with said head. Actuating arms 26 are carried by the shaft 23 and have their upper ends engaging within openings 27 formed in the rear edge portion of the unit. Thus, upon swinging of the lever 24, the shaft 23 will be turned or rotated and a lateral or transverse sliding movement will be imparted to the unit due to the arms 26 engaging within the openings 27. A lug 28 is formed on the upper end of the lever for engaging the forward face of the head so as to limit turning of the shaft and inward or rearward movement of the unit.

On other types of machines the lever 24 has its upper end extended the same as actuating arms 26, and engaging an opening in the rail much the same as openings 27. The lever 24 in this type of unit is not attached to the shaft 23, but pivots thereon, and lateral movement or retraction of the unit is attained by a direct action of the extended lever 24, the arms 24 maintaining parallelism of the rail unit in relation to the head.

As is clearly shown in Figs. 6, 7 and 8, the unit A is flat and preferably composed of three independent sections, a main matrix supporting section 30, a longitudinally movable supporting section or rail portion 31, and a bridging section or element 32. The section 30 has the openings 27 formed therein and consists of an elongate rectangular plate or member having a longitudi-

dinally extending lug 33 at the left-hand end of its rearward edge. In the retracted position of the upper rail, the forward edge of the lug 33 engages the left-hand spacer or bearing block 17 to limit the forward motion of the upper rail unit A.

The right-hand end of the main section 30 is divided by a longitudinally extending, rectangular slot or notch 34, said notch bifurcating or dividing the right-hand end of the section 30 into a pair of relatively wide, longitudinally extending fingers 35 and 36, respectively. The forward finger 35 is somewhat wider than the rearward finger 36 and is of greater length, as is clearly shown in Figs. 6, 7 and 8. The rearward edge of the rearward finger 36 is cut away at an angle for a portion of its length and beveled or undercut at 37, as shown in Figs. 7 and 9.

The longitudinally movable section 31 forms an extension of the matrix-supporting edge of the main section 30 and is substantially rectangular in shape with a triangular beveled lug or gate 38 adapted to be received in the cut away portion 37 to position the rearward edges of the sections 30 and 31 in longitudinal alinement. The section 31 also carries an elongate rectangular lug or retaining guide 39 having a snug sliding fit within the slot or notch 34, the guide 39 extending parallel to the gate 38 whereby the section 31 may undergo limited longitudinal movement with respect to the main section 30. However, it is pointed out that the engagement of the rearward finger 36 between the gate 38 and the guide 39 prevents lateral movement or shifting of the section 31 with respect to the section 30 so that as the latter is shifted laterally by means of the handle or lever 24, the section 31 is caused to be laterally shifted therewith. It is also pointed out that the section 31 undergoes only limited longitudinal movement with respect to the section 30 so that the gate 38 is always partially engaged within the cut away portion 37 and a substantially continuous matrix-supporting surface thus provided at all times by the rearward edge portions of said sections 30 and 31. Obviously, any desirable or suitable type of sliding joint between the sections 30 and 31 may be employed so long as such joint permits longitudinal shifting of the sections, one with respect to the other, while providing a substantially continuous supporting surface for the matrices which are fed onto the upper rail unit A from the typesetting machine.

The longitudinally shiftable section 31 carries a triangular notch 40 in its forward edge, the notch being so positioned as to have one leg 41 in substantial alinement with the right-hand end of the forward finger 35 when the section 31 is in its right-hand position as shown in Fig. 7. The bridging element or section 32 extends transversely along the right-hand end of the plate 30 adjacent the star wheel 21. The section 32 abuts the right-hand end of the finger 35 and is of a length substantially equal to the combined width of the sections 30 and 31, whereby the rear end of said section 32 is in substantial alinement with matrix-supporting edge of said sections. An offset, preferably rectangular, lug or tongue 42 projects rearwardly from the bridging section at its outer edge portion and its inner surface engages the outer end of a longitudinally extending lug 43 formed upon the right-hand end of the section 31. Although the particular shape of the tongue is not essential, the same should be only of a width sufficient to support a single matrix M in the position shown in Fig. 4, the rear marginal

edge of the tongue being alined with the longitudinal edges of the sections 30 and 31 so as to form a continuation of the upper rail constituted by said sections.

The forward end of the bridging section 32 projects beyond the forward edge of the plate 30 and has a lateral flange or lip 44 formed thereon for engaging said forward edge. Thus, retraction of the sections 30 and 31 will result in retraction of the bridging element 32.

For moving the element 32 laterally of the head 11 and independently of the other sections of the unit A, a lever 45 is journaled upon the shaft 23 and is provided with an upstanding arm 46 which is adapted to engage within an opening 47 formed in the forward edge portion of said element. By rocking the lever 45 upon the shaft 23, the arm 46 may be swung forwardly and rearwardly so as to move or slide the element in similar directions. Due to the provision of the lateral lip 44, rearward or reverse movement of the element will slide the other sections of the unit A rearwardly in the event that the same have been moved forwardly. Thus, the sections of the unit may be moved together in a forward direction by manipulating the lever 24 and in the opposite direction by means of the lever 45.

The section 32 carries a rearwardly extending, triangular lug 46' as a continuation of its left-hand side. As shown in Figs. 7 and 8, the lug 46' is so positioned as to be in substantial alinement with the triangular recess 40, and as shown in Fig. 6 engages within said recess when the section 32 is in its rearward position and the section 31 is in its right-hand position. The provision of the triangular notch and lug, 40 and 46', permits the automatic return of the section 31 to its right-hand position when the section 32 is moved to its rearward or bridging position. Thus, assuming the section 32 to be in its forward or non-bridging position and the section 31 to have been shifted to its left-hand position, the various elements will bear the relation illustrated in Fig. 8. Now, upon the return of the section 32 to its bridging position, the angular face of the lug 46' engaging the angular face of the recess 40 will cause the section 31 to be shifted to the right, as shown in Fig. 6. In this manner, each time the section 32 is returned to its bridging position, the section 31 is automatically shifted or returned to its right-hand position and a substantially continuous upper rail for supporting matrices is provided.

A recess 47' is formed in the lower surface of the bar 15 and receives a leaf or flat spring 48 which is secured within said recess by means of suitable screws 49. The free end of the spring 48 presses upon the upper surface of the upper rail unit A for holding said unit in engagement with the flat upper surface of the head 11. Being held in frictional engagement with the upper surface of the head, the unit is not subject to accidental or unintentional movement with respect to said head. If desired, one or more spring-pressed balls 50 may be mounted in the upper surface of the head 11 so as to engage the under surface of the unit A, and are preferably disposed beneath the plate or main section 30 with the ball engaging within a complementary depression or opening 51 when the unit A is in its rearward-most position.

In the operation of the assembler, matrices M are fed through the throat 20 and will be guided onto the rails by the star wheel 21 in the usual manner. When the upper rail unit A is in the position shown in Figs. 1 through 6, the

matrices will be supported upon and moved to the left along the sections 30 and 31 away from the throat and star wheel as additional matrices are fed and directed onto said rail. Whenever it is desired to feed one or more matrices onto the lower rail 14, the lever 45 is rocked upon the shaft 23 so as to swing the arm 46 forwardly and retract the bridging element 32 with its tongue 42. As is shown in Fig. 7, the retraction of the bridging element will leave a space or opening at the right-hand end of the rail portion 31 adjacent the star wheel, which space or opening is of sufficient width to accommodate only a single matrix M. Thus, whenever the bridging element is retracted, matrices will be fed directly upon the lower rail 14.

Due to the narrow width of the bridging tongue, the star wheel will normally kick or move the matrices assembled upon the upper rail unit beyond said tongue so that said matrices will be supported by the sections 30 and 31. This movement to the left of the assembled matrices will be materially assisted by the conventional space-band (not shown) which will usually be interposed between each change of type and the weight and size of which will cause said assembled matrices to move further to the left, whereby no matrices will be resting upon the tongue 43 upon retraction of the element 32.

It sometimes happens that a matrix will bind or hang upon the exposed end of the right-hand lug 43 between said lug and the star wheel due to the matrix being of excessive thickness or having an irregularity such as a burr, thereon. In this event, subsequently fed matrices would be prevented from passing through the space and onto the lower rail. However, due to the longitudinally-shiftable mounting of the rail portion 31, the binding or hanging of a matrix will force or move the section 31 to the left, causing the gate 38 to telescope the cut-away portion 37, until the high point or tooth of the star wheel has passed. As soon as this occurs, the matrix is no longer under a restraining force and will drop onto the lower rail through the space. Having been shifted to the left, the section 31 will remain in its new position and provide additional clearance or space through which matrices may fall. Thus, matrices may be fed directly upon the lower rail without manipulation by the operator each time a matrix is fed upon said rail. By returning the bridging element to its original or projecting position, the tongue 42 will again be alined with the rail portion 31 whereby the matrices will be fed upon the upper rail. Whenever ordinary or light face type is being set without mixed type, the entire unit A may be retracted by swinging the lever 24 so as to turn the shaft 23 and swing the arms 26 forwardly. Due to the provision of the lip 44, the bridging element 32 will be retracted upon swinging of the lever 24. In order to return the unit to its original or projected position, it is only necessary to rock the lever 45 which will result in the rearward movement of the entire unit.

From the foregoing, it is manifest that simple, economical upper rail unit has been provided and that the same is adapted to be mounted upon, or incorporated in, any type of duplex rail assembling elevator or assembler. The matrices may be fed onto either the upper or lower rail without excessive manipulation or concentration of the operator, whereby the latter may devote his time to the keyboard. The rail portion section 31 of the unit is slidable longitudinally rela-

tive to the other sections and the bridging element may be moved relative to the other sections. Also, the entire unit may be moved laterally or transversely by manipulation of the levers 24 or 45 to retract and project said entire unit. Since the tongue 42 is only of a width sufficient to accommodate a single matrix, there is no danger of a matrix accidentally falling to the lower rail upon retraction of the bridging member. Of course, the tension of the star wheel which is imposed upon the composed or assembled matrices is utilized to assure said matrices being moved beyond or past the tongue 42 prior to retraction of the same. Attention is also directed to the fact that matrices may be fed directly onto the lower rail while the upper rail is supporting other matrices.

The telescoping of the section 31 with respect to the section 30 is important in that such movement takes place entirely within the confines of the elevator frame 10 whereby no portions of the rail unit A project any time from said frame. With this structure, the invention may be applied to any standard form of typesetting machine without alteration of any portion of the machine other than the elevator itself. The speed and economy of installation is thus materially improved.

A modified form of the bridging section 32 is shown in Fig. 10 of the drawings. This modified form, designated by the numeral 32', is substantially identical to the section 32 and carries in addition an upstanding lug or tit 32 upon the extreme right-hand portion of the lug. The addition of this lug 52 is desirable when this invention is to be incorporated into the assembly elevators used upon certain models of typesetting machines which have a retaining plate covering only the lower or fixed rail.

The foregoing description of the invention is explanatory thereof and various changes in the size, shape and materials, as well as in the details of the illustrated construction may be made, within the scope of the appended claims, without departing from the spirit of the invention.

What we claim and desire to secure by Letters Patent is:

1. A duplex rail assembling elevator including, a frame, a lower rail mounted on the frame, and an upper rail unit carried by said frame and disposed above the lower rail, at least a portion of the upper rail being movable longitudinally with respect to the frame, the unit having a section movable laterally with respect to the frame so as to expose a portion of said lower rail, the longitudinally movable portion of the upper rail having a recess in one longitudinal edge thereof spaced from the ends of said longitudinally movable portion, and the section carrying a projection engaging within said recess in one position of said section to prevent any longitudinal movement of said portion.

2. A duplex rail assembling elevator including, a frame, a lower rail mounted on the frame, an upper rail unit carried by said frame and disposed above the lower rail, the unit having a section movable laterally with respect to the frame so as to expose a portion of said lower rail, the remainder of the upper rail being divided into two portions, one of which is movable longitudinally of the frame and with respect to the other, the laterally moving section carrying a projection engaging within a recess in the longitudinally movable portion of the rail in one posi-

tion of said section to prevent any longitudinal movement thereof.

3. A duplex rail assembling elevator including, a frame, a lower rail mounted on the frame, and an upper rail unit carried by said frame and disposed above the lower rail, the unit having an independently retractile section for exposing a portion of said lower rail so that retraction of the section permits feeding of matrices directly onto the lower rail while said unit supports other matrices, a portion of the rail unit which supports matrices upon retraction of said section being movable longitudinally away from said section and with respect to the remainder of said rail unit, whereby said portion may undergo longitudinal movement away from the section upon binding of matrices being fed directly onto the lower rail so as to permit said matrices to fall onto said rail, and a connection between the retractile section and the longitudinally movable portion of the rail for causing the latter portion to be returned toward the section upon extension of said section to an unretracted position.

4. A duplex rail assembling elevator including, a frame, a lower rail mounted on the frame, and an upper rail unit carried by said frame and disposed above the lower rail, the unit having an independently retractile section for exposing a portion of said lower rail so that retraction of the section permits feeding of matrices directly onto the lower rail while said unit supports other matrices, a portion of the rail unit which supports matrices upon retraction of said section being movable longitudinally away from said section and with respect to the remainder of said rail unit, whereby said portion may undergo longitudinal movement away from the section upon binding of matrices being fed directly onto the lower rail so as to permit said matrices to fall onto said rail, and a wedge connection between the retractile section and the longitudinally movable portion of the rail for causing the latter portion to be returned toward the section upon extension of said section to an unretracted position.

5. A duplex rail assembling elevator including, a frame, a lower rail mounted on the frame, and an upper rail unit carried by said frame and disposed above the lower rail, the unit having an independently retractile section for exposing a portion of said lower rail so that retraction of the section permits feeding of matrices directly onto the lower rail while said unit supports other matrices, a portion of the rail unit which supports matrices upon retraction of said section being movable longitudinally away from said section and telescoping the remainder of said rail unit, whereby said portion may undergo longitudinal movement away from the section upon binding of matrices being fed directly onto the lower rail so as to permit said matrices to fall onto said rail, and a connection between the retractile section and the longitudinally movable portion of the rail for causing the latter portion to be returned toward the section upon extension of said section to an unretracted position.

6. A duplex rail assembling elevator including, a frame, a lower rail mounted on the frame, and an upper rail unit carried by said frame and disposed above the lower rail, said upper rail providing a substantially continuous matrix-supporting surface, the unit having an independently retractile section adapted to be retracted for exposing a portion of said lower rail so that matrices may be fed directly onto the lower rail

while the balance of the upper rail unit supports other matrices, said balance of the rail unit including at least two matrix-supporting sections, one of the latter sections being movable longitudinally with respect to the other and with respect to the longitudinal axis of the frame, a wedge carried by the longitudinally movable section, a wedge carried by the independently retractile section and engaging the first named wedge, whereby return of the retractile section to an unretracted position causes the engaging wedges to shift the longitudinally movable sections with respect to the remaining section of the rail unit.
